ELECTROMAGNETIC RELAY DEVICE

Filed March 22, 1943

UNITED STATES PATENT OFFICE

2,410,279

ELECTROMAGNETIC RELAY DEVICE

John A. Favre, Drexel Hill, Pa., assignor to General Electric Company, a corporation of New York

Application March 22, 1943, Serial No. 480,024

9 Claims. (Cl. 175—337)

1

My invention relates to improvements in electromagnetic relay devices and more particularly to relay devices for controlling circuits in a pre-determined order, and especially to relay devices the operation of which is substantially unaffected by low frequency vibrations and which are relatively insensitive to shock.

It is often necessary alternatively to connect an electrical device to one or the other of two other electrical devices. Thus, in radio communication, it is desirable alternatively to connect the aerial to a transmitter or a receiver. Obviously, a device for controlling such connections must be so positive in its action as to insure the connection to the aerial of the desired device, regardless of which of the devices was last connected thereto. Moreover, if the radio communication equipment is subject to relatively low frequency vibrations and also to shocks, as in installations aboard aircraft, it is especially important that neither the connection of the device in use nor the connection of the device that it is desired to use be disturbed or prevented in consequence of such shocks or vibrations. In other words, if the connection is not positively made and maintained, regardless of shocks and vibrations, the operator may find himself receiving when he wants to send and vice versa. This might well be dangerous, as in the case of an airplane trying to find and land at an airport under bad weather conditions. Moreover, in the application of electromagnetic relay devices, particularly to aircraft, it is important to avoid the necessity of maintaining the devices continuously energized in order to minimize the drain on the power supply, decrease the weight of the devices, and reduce the possible fire hazard from overheated windings.

An object of my invention is to provide a relatively simple and economical electromagnetic relay device by which one electrical device can be connected to either one of two other electrical devices alternatively with a positive action substantially unaffected by low frequency vibrations and shocks. Another object of my invention is to provide an alternative operation electromagnetic relay device which is capable of maintaining the function last performed without the necessity for keeping the device continuously energized. These and other objects of my invention will appear in more detail hereinafter.

In accordance with my invention, I provide an improved electromagnetic relay device wherein two electromagnetic elements are coordinated in such a manner that the operation of each is dependent on the operation of the other to obtain

2

a desired selectivity of switching operations and, substantially regardless of vibrations and shocks, a positive maintenance of the last connection until such time as another change is desired without the necessity of maintaining the device continuously energized.

My invention will be better understood from the following description when considered in connection with the accompanying sheet of drawings. 10 and its scope will be pointed out in the appended claims.

In the accompanying sheet of drawings, Fig. 1 is a side elevation of an electromagnetic relay embodying my invention with the parts shown in one switching position; Fig. 2 is a top plan view of the embodiment of my invention shown in Fig. 1; Fig. 3 is a partial side elevation of the embodiment of my invention shown in Fig. 1 similar thereto but with the parts shown in a different switching position; and Fig. 4 is a schematic perspective and diagrammatic arrangement illustrating the embodiment of my invention shown in Figs. 1, 2 and 3 as applied to an alternative switching arrangement.

25 In the illustrated embodiment of my invention, I have shown an electromagnetic relay device comprising two electromagnetic elements 6 and 7, respectively, having energizing windings 8 and 9 and armatures 10 and 11. The electromagnetic elements 6 and 7 are suitably secured to a base 12 of suitable insulating material. For economy of space and simplicity in structure, the windings 8 and 9 may be arranged as two spaced substantially coaxial solenoids, as shown. Also, in accordance with my invention, the armature 10 is of the plunger type, and the armature 11 of the hinged type. Also, as illustrated, the electromagnetic element 6 includes a stationary magnetic structure comprising a generally U-shaped magnetic member 13 and a pole piece 14, and the electromagnetic element 7 includes a magnetic core and pole piece 15 and a generally U-shaped magnetic member 16, the leg 17 of which is suitably shaped to provide a bearing support for the armature 11. The armatures 10 and 11 are independently biased to their unattracted positions by suitable means, such as springs 18 and 19 respectively.

In accordance with my invention, I provide 50 means for suitably coordinating the movements of the armatures 10 and 11 so as to obtain a desired alternative switching arrangement and maintenance of the function last performed without the necessity of keeping the electromagnetic elements 6 and 7 continuously energized. As

shown, this means includes a member 20 which is mounted to partake of the movement of the armature 10 and is operative upon movement thereof to the unattracted position while the armature 11 is in the attracted position to hold this armature in its attracted position after deenergization of its associated winding 9. Also, the member 20 is operative upon movement of the armature 10 to the attracted position to release the armature 11 for movement to the unattracted position under the bias of the spring 18. In its unattracted position the armature 11 is effective to maintain the armature 10 in the attracted position against the bias of the spring 18. In other words, each armature is effective to hold the other armature in its attracted position so as to maintain the function last performed without the necessity of maintaining the associated energizing winding continuously energized.

In order to obtain the foregoing operation, the member 20 is arranged to be moved into and out of holding engagement with the armature 11 and vice versa. For this purpose, the member 20 may be mounted directly near the outer end of the plunger armature 10 and arranged to engage the armature 11 through its angularly extending leg 21 which is pivotally supported on the magnet leg 17 by suitable means, such as a pin 22. In accordance with our invention, the pivotal support 22 of the armature member 11-21 is substantially at the center of gravity of this member for dynamic balance in order to minimize response to shocks and vibrations. Clockwise rotation of the armature member 11-21 is limited by suitable means such as the head of the pin 22 and a projection 21' on the lower side of the leg 21. As shown, the biasing spring 19 is a tension spring which is connected between a stationary pin 23 and the armature extension 21. The member 20, which in Figs. 1, 2 and 4 is shown in the unlatched position under the end of the armature extension 21, is held in place on the armature 10 by suitable means, such as a lock washer 24 and a nut 25. For guiding the outer end of the armature 10, it may be provided with a reduced diameter extension 26 which is guided in a cylindrical hole in the core 15, as shown in Fig. 1. In order to maintain the desired alignment of the latching member 20 during movement thereof so that it will always be correctly positioned relatively to the end of the extension 21, the lower end of the member 20 is provided with a suitable notch 27, as shown in Fig. 4, which engages a guide rod 28 mounted between the magnetic members 13 and 16, as shown in dotted lines in Fig. 1.

Further in accordance with my invention, I provide in circuit with the winding 8 switching means which is arranged to be controlled by the movement of the armature 11 and is operative upon movement thereof to the unattracted position to open the circuit of the winding 8. As shown, this switching means comprises a movable conducting member 29 which may have a generally U-shaped form, as shown more clearly in Fig. 4, and which is arranged to partake of the movement of the armature 11 and may be secured directly thereto as shown. This switching member 29 is provided with two contact portions 30, 30' which, in the attracted position of the armature 15, engage stationary contacts 31, 31' associated with terminals 32, 32' suitably mounted on the base 12.

Also, in accordance with my invention, I provide in circuit with the winding 9 switching

means which is arranged to be controlled by the movement of the armature 10 and which is operative upon movement thereof to the unattracted position to effect deenergization of the winding 9. As shown, this switching means comprises a T-shaped, circuit controlling member 33 which is mounted to move with the armature 10. For this purpose, it may be mounted on the armature to seat against a shoulder thereon just back of the latching member 20, as shown more clearly in Figs. 1 and 3. In Fig. 4, the latching member 20 and the circuit controlling member 33 are, for purposes of clearness in the diagrammatic showing, illustrated much farther apart than is actually the case. In order to maintain the alignment of the circuit controlling member 33, it is provided with a suitable notch 34 which engages the guide rod 28. The biasing spring 18 is shown as a compression spring mounted between the magnet leg 35 and the leg of the circuit controlling member 33.

As shown, the circuit controlling member 33 is provided with two contact carrying arms 36 and 37 and is, in effect, a double pole double throw switch. The contact arm 36 is provided with a contact 38, and the contact arm 37 is provided with a contact 39. In the attracted position of the plunger armature 10, the contact 38 is arranged to engage a contact 40 secured to a terminal 41 on the base 12, and the contact 39 is arranged to engage a contact 42 secured to a terminal 43 mounted on the base 12. In the unattracted position of the plunger armature 10, the contact 38 is arranged to engage a contact 44 secured to a terminal 45 mounted on the base 12 and the contact 39 is arranged to engage a contact 46 secured to a terminal 47 mounted on the base 12. The base 12 may further be provided with terminals 50 and 51 for permanent connections to the base and flexible connections to the contact arms 37 and 36, respectively. For simplicity in assembly and general rigidity of structure as well as to secure the desired high insulating properties required for use under certain conditions, the contact terminals 32, 32', 41, 43, 45, 47, 50 and 51 may be mounted on contact rails 52 and 53 of suitable insulating material secured to the base 12, as shown more clearly in Fig. 2. Further terminals 54 and 55 are also provided for connections which do not require such a high degree of insulation.

In order to prevent false operation of the electromagnetic device above described under vibrations particularly of a relatively low frequency and under substantial shock especially so as not to affect the positive closing of the contacts and maintaining them closed, I keep the mass of the moving parts relatively small and use relatively strong springs. Also, for freedom from shock in the latched position, the construction of the latch member 20 and the armature 11 and its mounting is such as to provide the maximum resistance to dynamic unbalance. The combination of the relatively strong, plunger type electromagnet 6 with the dynamically balanced, hinged armature member 11-21 of the electromagnet 7 provides a good shock- and vibration-proof relay because the spring 18 furnishes sufficient force to hold the armature 10, the latch 20, the contact arm 33, and associated contacts in the unlatched position, as shown in Figs. 1, 2 and 4, even under conditions of shock and vibration such as this relay is intended to withstand. To facilitate this, the moving parts 18, 10, 20, 33, etc., are made as light as possible.

When the relay is in the latched position shown in Fig. 3, it is maintained in that position under conditions of vibration or shock by the extension 21 of the dynamically balanced armature member 11—21 latching with the member 20 under the bias of the spring 19. In other words, in the unlatched position shown in Figs. 1, 2 and 4, the spring 18 overcomes the inertia of the light-weight parts and prevents motion or separation of the contacts 39, 46 and 38, 44 relatively to each other. Similarly, in the latched position, as shown in Fig. 3, the dynamically balanced armature member 11—21 insensitive to shock and assisted by spring 19 holds the member 20 in positive contact against the pressure of spring 18 thereby maintaining the contacts 39, 42 and 38, 40 in a positively closed condition.

For the purpose of explaining my invention, it will be assumed that it is desired to connect alternatively and at will the terminal 50 to one or the other of the terminals 43 and 47 in response to the operation of two manually controlled switches 56 and 57, shown only in Fig. 4. Assuming first that the last operation performed was such as to leave the parts positioned as shown in Figs. 1, 2 and 4, then the terminal 50 is connected to the terminal 47 through a flexible lead 50', the switch arm 37 and the contacts 39 and 46. If now it is desired to change the connection so as to connect terminal 50 to terminal 43, then the switch 56 is closed. Then, with reference to Fig. 4, this completes the circuit of the winding 8 of the electromagnetic element 6 as follows: from one side of the source, indicated as plus, through the switch 56, a conductor 58, the terminal 32, the contacts 31 and 30, the switch arm 29, the contacts 30' and 31', the terminal 32', a conductor 59, the winding 8, a conductor 60, and the terminal 54 to the other side of the source, indicated as minus. Upon completion of the circuit of the winding 8, the armature 10 is moved to the attracted position since the circuit of the winding 9 is open at contacts 38 and 40, as will be obvious from Fig. 4. Upon movement of the armature 10 to the attracted position, the contact 39 is moved from contact 46 to contact 42 to bring about the desired switching change. At the same time, the contact 38 is moved to engage the contact 40. Upon movement of the latch 20, the armature 11 under the bias of the spring 19 moves to the unattracted position and the contacts 31, 30 and 31', 30' are separated, thereby opening the circuit of the winding 8. The latch 20 is now positively held in the latched position since the end of the armature extension 21 falls behind it under the bias of the spring 19 so as positively to maintain the contacts 39, 42 and 38, 40 in the closed position while the contacts 30, 31 and 30', 31' are positively maintained in the open position by the force of the spring 19.

If now it is desired to switch back to the original position, that is to say, to connect the terminal 50 to the terminal 47, then the switch 57 is closed. This completes the circuit of the winding 9 from one side of the source, indicated as plus, through the switch 57, a conductor 61, the terminal 41, the contacts 40 and 38, the switch arm 36, a conductor 62, the terminal 51, a conductor 63, the winding 9, a conductor 64, and the terminal 55 to the other side of the source, indicated as minus. Upon energization of the winding 9, the armature 11 is moved to the attracted position which takes the blocking action away from the armature 10. Consequently, under the strong bias of the spring 18, the armature 10, the switch-

ing member 33 and the latch member 20 are quickly returned to the position shown in Fig. 1 to restore the connections to the condition shown in Fig. 4.

While I have indicated the sources of energization of the windings 8 and 9 by plus and minus busses, it is to be understood that my invention is not limited to energization by direct current but is equally applicable to an alternating current source of energization.

From the foregoing, it will be observed that in either the attracted or unattracted positions of the armatures 10 and 11, they are forcibly blocked or held against movement which prevents any false operation of the switching members 29 and 33 in consequence of relatively severe vibrations and shock. Moreover, it will be apparent that the blocking action once it is established is independent of energization of the windings 8 and 9. Also, it will be observed that because of the coordinated arrangement of the two armatures, if the operator should inadvertently push the wrong switch, that is to say, if the switch 57 were inadvertently actuated while the parts are positioned as shown in Figs. 1 and 4, there would be no change in the switching connections. In other words, the arrangement of the parts is such that the relay device is so positive in its action as to insure the connection of one device to either of two desired devices, regardless of which of these last devices was last connected to the one device.

The conductors 50', 58, 59, 60, 61, 62, 63, and 64, referred to in connection with Fig. 4, are not shown in Figs. 1, 2 and 3 in order to avoid confusion in illustration of structure.

While I have shown and described my invention in considerable detail, I do not desire to be limited to the exact arrangements shown, but seek to cover in the appended claims all those modifications that fall within the true spirit and scope of my invention.

What I claim as new and desire to secure by Letters Patent of the United States is:

1. An electromagnetic device comprising a hinged armature and a plunger armature, each armature having a blocking and a blocked position, means for mechanically interlocking said armatures to prevent movement of either armature from its blocked position to its blocking position when the other armature is in its blocking position, means for moving an armature from its blocking position to its blocked position, and means for moving an armature from its blocked position to its blocking position when the other armature is moved to its blocked position.

2. A relay device comprising two electromagnetic elements, each having an energizing winding, a dynamically balanced hinged armature associated with one of said windings, a plunger armature associated with the other of said windings, means independently biasing each of said armatures for movement to the unattracted position, and means controlled by the movement of said armatures operative upon movement of either armature to the attracted position and the other armature to the unattracted position to maintain the attracted armature in the attracted position irrespective of the maintenance of the energization of the associated winding.

3. An electromagnetic relay device comprising two spaced substantially coaxial solenoids, a plunger armature associated with one of said solenoids and a hinged armature associated with the other of said solenoids, the movements of said

armatures being arranged to be controlled in response to the energization of said solenoids, resilient means independently biasing each of said armatures for movement to the unattracted position, and a member mounted between said solenoids to partake of the movement of said plunger armature and constructed and arranged upon movement thereof to the unattracted position while the hinged armature is in the attracted position to hold the hinged armature in the attracted position after deenergization of its associated solenoid and upon movement of the plunger armature to the attracted position to release the hinged armature for movement to the unattracted position, said hinged armature being constructed and arranged upon movement to the unattracted position to abut said member and hold said plunger armature in the attracted position.

4. A relay device comprising two electromagnetic elements, one having a plunger armature and the other a hinged armature, each of said armatures being independently biased for movement to the unattracted position, and a member mounted to partake of the movement of said plunger armature operative upon movement thereof to the unattracted position while the hinged armature is in the attracted position to hold the hinged armature in the attracted position after deenergization of its associated electromagnetic element and upon movement of the plunger armature to the attracted position to release said hinged armature for movement to the unattracted position, said hinged armature being constructed and arranged upon movement to the unattracted position to engage said member and hold said plunger armature in the attracted position.

5. A relay device comprising two electromagnetic elements, each having an energizing winding, a plunger armature associated with one of said windings, a hinged armature associated with the other of said windings, means independently biasing each of said armatures for movement to the unattracted position, and a member mounted to partake of the movement of said plunger armature operative upon movement thereof to the unattracted position while said hinged armature is in the attracted position to hold the hinged armature in the attracted position after deenergization of its associated winding and upon movement of said plunger armature to the attracted position to release said hinged armature for movement to the unattracted position, said hinged armature being constructed and arranged upon movement to the unattracted position to engage said member and hold said plunger armature in the attracted position.

6. An electromagnetic relay device comprising

two spaced substantially coaxial solenoids, one having a plunger armature and the other a hinged armature, each of said armatures being independently biased for movement to the unattracted position, and a member mounted between said solenoids to partake of the movement of said plunger armature and constructed and arranged upon movement thereof to the unattracted position while the hinged armature is in the attracted position to hold the hinged armature in the attracted position after deenergization of its associated solenoid and upon movement of the plunger armature to the attracted position to release said hinged armature for movement to the unattracted position, said hinged armature being constructed and arranged upon movement to the unattracted position to abut said member and hold said plunger armature in the attracted position.

7. An electromagnetic device comprising a hinged armature and a plunger armature, each armature having a blocking and a blocked position, means for mechanically interlocking said armatures to prevent movement of either armature from its blocked position to its blocking position when the other armature is in its blocking position, means comprising two spaced substantially coaxial solenoids respectively associated with said armatures for moving the associated armature from its blocking position to its blocked position, and means for moving each armature from its blocked position to its blocking position when the other armature is moved to its blocked position.

8. A relay device comprising an electromagnet having a hinged armature, a rectilinearly movable member for blocking said armature in one position, means tending to move said member to the blocking position, electromagnetic means for moving said member from the blocking position, and means tending to move said armature to another position upon movement of said member from the blocking position, said armature being arranged in said other position to engage said member when out of the blocking position to prevent movement of the member to the blocking position.

9. A relay device comprising an electromagnet having a hinged armature, a rectilinearly movable member for blocking said armature in the attracted position, resilient means tending to move said member to the blocking position, electromagnetic means for moving said member from the blocking position, and resilient means tending to move said armature to the unattracted position upon movement of said member from the blocking position, said armature being arranged in the unattracted position to engage said member when out of the blocking position to prevent movement of the member to the blocking position.

JOHN A. FAVRE.
